UNITED STATES PATENT OFFICE

173,266

FLOW CONTROL VALVE FOR ABOVE-GROUND IRRIGATION PIPES

Martin J. Kelly, Grand Island, Nebr.

Application July 16, 1953, Serial No. 25,969

Term of patent 14 years

(Cl. D91—3)

To all whom it may concern:

Be it known that I, Martin J. Kelly, a citizen of the United States of America, residing at Grand Island, in the county of Hall and State of Nebraska, have invented a new, original, and ornamental Design for Flow Control Valves for Above-Ground Irrigation Pipes, of which the following is a specification, reference being had to the accompanying drawing, forming a part hereof.

In the drawing:

Fig. 1 is an outside perspective view of a flow control valve for above-ground irrigation pipes, showing my new design; and

Fig. 2 is a similar inside view thereof.

I claim:

The ornamental design for a flow control valve for above-ground irrigation pipes, as shown.
